GOLF CLUB CART

Lucien M. Flagg, Bethlehem, Pa.

Application September 1, 1954, Serial No. 32,100

Term of patent 7 years

(Cl. D14—3)

Fig. 4.

Figure 1 is a perspective view of a golf club cart with the seat in collapsed position and showing my new design;

Figure 2 is a perspective view of the cart taken from a different angle and showing the seat in an opened position;

I claim:

The ornamental design for a golf club cart, substantially as shown and described.
